UNITED STATES PATENT OFFICE.

MILTON F. WILLIAMS, OF ST. LOUIS, MISSOURI, ASSIGNEE TO WILLIAMS PATENT CRUSHER & PULVERIZER COMPANY, OF ST. LOUIS, MISSOURI, A CORPORATION OF MISSOURI.

SHREDDING-HAMMER.

1,078,650.

Specification of Letters Patent.

Patented Nov. 18, 1913.

Application filed May 31, 1913. Serial No. 771,107.

To all whom it may concern:

Be it known that I, MILTON F. WILLIAMS, a citizen of the United States, residing at St. Louis, Missouri, have invented a certain 5 new and useful Improvement in Shredding Hammers, of which the following is a full, clear, and exact description, such as will enable others skilled in the art to which it app pertains to make and use the same, reference 10 being had to the accompanying drawings, forming part of this specification, in which—

Figure 1 is a sectional elevation of a rotary mill showing the application of my 15 invention. Fig. 2 is a perspective view of one form of my invention. Fig. 3 is a perspective view of a modified form of my invention.

My invention relates broadly to milling 20 and specifically to a form of shredding hammer for use in rotary mills.

The principal object of my invention is to produce an economical and efficient shredding hammer.

25 A further object of my invention is to provide a rigid shredding hammer having small or fine shredding units, yet having the requisite weight to insure effective operation.

30 A further object of my invention is to provide a shredding hammer which will be self-clearing and not subject to clogging by shredded material.

Other and further objects of my invention 35 will be obvious or hereinafter pointed out.

Referring to the drawings it will be understood that my improved hammer is for use in a rotary mill 1 wherein mounting disks 2 are carried on the shaft 4, and the hammers 5 are pivotally mounted at 6 on the 40 disks 2. A suitable concave 7 is adapted to coöperate with the hammers 5, in the reduction of the material which is introduced into the feed hopper 8.

In the fine shredding of various materials 5 it is essential that the cutting or shredding elements be quite thin or fine in order to shred the material to the desired degree of fineness. Moreover, in rotary shredding mills of the sort illustrated it is essential that the shredding members possess a high degree of rigidity or stability so as to prevent their being distorted, or their action diverted, due to the great force with which they are operated, and the resistance to which they are subjected. Moreover, it is

desired that such pivoted shredding members have weight sufficient to insure their acting effectively upon the material, which action is accomplished by their being held out radially of the shaft by centrifugal force. The form of shredding hammer here illustrated, and which I consider my invention, possesses these several attributes in addition to being economical to manufacture, easy to sharpen and repair, of effective 60 form for various shredding operations, and self-clearing.

As illustrated in Fig. 2, my improved shredding hammer may be made up of a series of knife-like members 9, riveted together and having their points or operating ends 10 bent or flared apart from one another. The end edges and points 11 are suitably sharpened or formed according to the particular use to which the hammer is 70 put. A suitable means 12 is provided whereby the hammer may be mounted upon the actuating member. The flared operating ends 10 provide fine shredding elements 75 which are adapted to shred the material 80 acted upon very finely. Placed as they are close to one another, and firmly held in this relationship, the shredding edges operate very effectively on material, as they co-operate with one another to compress the 85 material between them and hold it positively to the action of the respective edges.

To avoid the possibility of finely shredded material becoming lodged in the space between the blades 9, and the efficiency of the 90 hammer decreased, clearing apertures 14 are provided through the blades 9, opening just below the line where the blades come into contact. Material which is forced between the blades readily escapes through these 95 apertures, and the space between the blades is thereby kept clear.

As illustrated in Fig. 3, the blades 9 may be disposed parallel to but separated from one another, instead of flared apart. This 100 form may be built up of separate blades riveted or welded together with suitable spacing strips between them, or this form may be cut out of a suitable bar.

From the foregoing description it will be 105 seen that my form of shredding hammer has decided advantages in that while the shredding elements are quite fine, they are at the same time quite rigid, and in operation each has the benefit of the momentum accruing 110

from the combined weight of all. Moreover, their relative location is such as to produce an intimate and effective coöperation between them when the device is acting upon material.

I am aware that further modifications in the device may be made without departing from the scope of what I claim to be my invention, and it is my intention that the following claims be construed to comprehend all such modifications.

I claim:

1. A shredding hammer consisting of a plurality of knife-like shredding elements separated at their operating ends, and conjoined in a common shank portion, certain of said shredding elements being provided with apertures for the purpose described.
2. A shredding hammer comprising a shank portion divided at one end into a plurality of operating members disposed apart from one another, each of said operating

members being provided with an aperture communicating with the space intermediate it and its adjacent operating members. 25

3. In combination with a rotary shaft and a concave, a shredding hammer mounted upon the shaft and adapted to coöperate with the concave, said shredding hammer comprising a plurality of thin shredding 30 members conjoined in a common shank portion and having their minimum width equal to the width of said shank portion, said operating members being provided with apertures communicating with the spaces 35 between them.

In testimony whereof I hereunto affix my signature in the presence of two witnesses, this 26th day of May, 1913.

MILTON E. WILLIAMS.
